DONALD BRATT, OF IRWIN, AND CARL J. FECHHEIMER, OF PITTSBURGH, PENNSYLVANIA, ASSIGNORS TO WESTINGHOUSE ELECTRIC AND MANUFACTURING COMPANY, A CORPORATION OF PENNSYLVANIA.

TURBO VENTILATION.

Application filed June 26, 1923. Serial No. 647,779.

To all whom it may concern:

Be it known that we, DONALD BRATT, a subject of the King of Sweden, and a resident of Irwin, in the county of Westmoreland and State of Pennsylvania, and CARL J. FECHHEIMER, a citizen of the United States, and a resident of Pittsburgh, in the county of Allegheny and State of Pennsylvania, have invented a new and useful Improvement in Turbo Ventilation, of which the following is a specification.

Our invention relates to the ventilation of dynamo-electric machines, and it has particular relation to turbo-alternators and other smooth-core machines which are characterized by a relatively great length in comparison with the diameter, rendering ventilation by means of the air-gap alone insufficient.

In machines of the class just mentioned, it has been customary to supply the cooling fluid from both ends of the air-gap, discharging the same through radial ducts in the stator. It has long been recognized that the ventilation from the ends of the air-gap could be supplemented by additional means for passing a cooling fluid into the intermediate parts of the air-gap through radial ventilating ducts in the stator, as set forth in the Swiss Patent No. 37,813, dated July 12, 1906.

As a result of the difficulty of predicting the air flow and velocities in any given machine, as well as the very great cost of the machines, the machines of the prior art have been laid out without special consideration of the radial velocities in the most restricted portions of the respective radial ventilating spaces.

It is the principal object of our present invention to provide a machine of the class hereinabove described, wherein substantially uniform temperature conditions are secured by means of approximately uniform radial velocities of cooling fluid in the radial ventilating spaces of the stator.

Another object of our invention is to provide such a machine in which groups of radial spaces are arranged for intake ducts and discharge ducts, respectively, the number of ducts in each group having a definite relation to the ratio between the radial duct area and the air-gap area, all as hereinafter pointed out.

Other objects and details of our invention will be apparent from the following description and claims and from the accompanying drawing, wherein:

Figure 1 is a sectional view showing a turbo-alternator of the type to which our invention relates,

Fig. 2 is a diagrammatic view explanatory of the mathematical treatment of the problem,

Fig. 3 is a curve diagram utilized in determining the relations of the various quantities involved,

Fig. 4 is another diagrammatic view accompanying the mathematical treatment, and

Figs. 5 and 6 are curve diagrams illustrating our invention.

In Fig. 1 is shown a turbo-alternator comprising a stator member 10, carrying alternating-current windings 11, and a rotor member 12, carrying direct-current field windings, the end turns of which are shown at 13. The stator and rotor members are both of the smooth-core type, and they are separated by an air gap 14.

The stator member 10 comprises a laminated magnetizable core 15 having a large number of radially disposed annular ventilating spaces 16 left between bunches of laminations 17. The radial ventilating spaces or ducts are divided into a plurality of groups surrounded by annular chambers 18, 19 and 20, the central and end chambers 20 and 18 being discharge chambers having discharge vents (not shown) and the intermediate chamber 19 being an intake chamber for forcing a cooling fluid radially inwardly through the corresponding radial spaces 16.

Cooling fluid is supplied to the end bells of the machine by any suitable means, such as fans 23 which are secured to the ends of the rotor member 12. The intake chambers 19 are likewise supplied with cooling fluid by any suitable means, such as ducts 24 connecting the same to the respective end-bell spaces.

The general operation of the ventilating system shown in Fig. 1 will be obvious. Cooling fluid admitted from the ends of the air-gap passes out through the nearest radial ducts 16 into the annular discharge chambers 18. Cooling fluid admitted from the annular intake chambers 19 passes ra-

dially inwardly to the air gap and thence divides and discharges through the radial ducts 16 associated with the adjacent annular discharge chambers 18 and 20, all as indicated by the arrows.

While prior constructions of the general type just described have had, for their object, the prevention of over-heating in the central portions of the machine, the designs 10 have all been directed either to the problem of avoiding the necessity for utilizing the ventilating air after it had become over-heated in a long passage through the air-gap to the central portions of the machine, or to 15 the problem of securing a sufficient air flow without resort to excessive pressure heads on account of the insufficient air-gap area in long machines.

According to our invention, the cooling is 20 effected very largely by means of the radially flowing air, the axial flow being relied upon to a much lesser extent, and the quantity of air being such that its increase in temperature in the machine is relatively 25 small. An important feature of our invention is that we aim to obtain uniformity of temperature conditions within the machine by securing, as nearly as possible, uniform radial velocities in the radial ventilating 30 spaces. If any variation should occur in the radial velocities, it is, of course, evident that somewhat lower velocities could be tolerated in the intake vents than in the discharge vents, on account of the necessarily lower 35 temperature of the intake air.

With the above-mentioned general principles in view, our invention consists further in the discovery of certain relationships necessary to exist between the number of radial 40 ventilating ducts in any group and the ratio of the radial duct area to the air-gap area, our invention being the culmination of a long and costly series of experiments. For facilitating the explanation of our invention, 45 reference will be made to a mathematical theory, with the understanding that we are not necessarily limited to any particular theory or explanation except as specified in the appended claims.

50 Neglecting variations in volume resulting from pressure and temperature changes, we may assume, with fair approximation, the validity of Bernoulli's well-known equation in hydraulics, namely, that the sum of the 55 pressure head and the velocity head is a constant quantity for any particle throughout its course in a given duct, neglecting losses of head. Reference will be had to the following notations, which will be made clearer by reference to Fig. 2:

x =axial co-ordinate of intake belt.

y =axial co-ordinate of discharge belt.

p =static pressure in tube (air gap) at x or y .

65 P =static pressure in pressure chamber.

v =axial air velocity in tube (air gap) at x or y .

V =radial air velocity in most restricted portion of radial vent at x or y .

a =cross-sectional area of tube (air gap). 70

S =cross-sectional area of a radial vent at its most restricted section.

γ =specific weight of air.

g =acceleration of gravity.

C_i =intake coefficient, definition: 75

$$\frac{P-p}{\gamma} = C_i \frac{V^2}{2g}$$

C_d =discharge coefficient, definition: 80

$$\frac{p}{\gamma} = C_d \frac{V^2}{2g}$$

L_i =number of radial vents in half of intake belt. 85

L_d =number of radial vents in half of discharge belt.

The coefficients C_i and C_d are introduced to compensate for the friction losses and are 90 constants depending upon the shape of the slots, the number of teeth, the depth of punching, the shape of wedge, etc. The coefficients are constant not only for any given machine, but, in general, for any size of machine of a given type, within the limits of 95 pressure and velocity encountered in practice. The terms C_i and C_d are evaluated largely by experiment. C_i appears to vary between the limits 1.05 and 1.30 for different 100 machines and C_d appears to vary between the limits 0.60 and 1.20. It appears, from our present knowledge, that C_d is equal to a constant having a value of probably about 0.7 or 0.8 plus a constant times $(S/a)^2$. The 105 above values are given for machines in which the slot wedges are cut away where they cut the radial ventilating spaces 16.

From Bernoulli's equation, we have

$$\frac{p}{\gamma} + \frac{v^2}{2g} = \text{const. } (1)$$

Also, from the definition of C_i , we have, for the intake, 115

$$\frac{p}{\gamma} = \frac{P}{\gamma} - C_i \frac{V^2}{2g},$$

which is substituted in equation (1), noting that $\frac{P}{\gamma}$ is a constant, giving 120

$$\frac{v^2}{2g} - C_i \frac{V^2}{2g} = \text{const. } (2)$$

125 In the same way, for the discharge, we find

$$\frac{v^2}{2g} + C_d \frac{V^2}{2g} = \text{const. } (3)$$

The equations (2) and (3) give the rela- 130

tion between v and V only. From the equation of continuity, we have

$$a.dv = S.V.dx,$$

5 which means that the increase in volume in the air-gap equals the volume of air taken in through the radial ducts. The equations (2) and (3) are readily transformed into a differential equation of the second order in 10 v and x , or (or in v and y , for the discharge). The solution of these differential equations and the proper determination of the integration constants, give the following formulae each of which corresponds to any 15 given group of radial ducts from the beginning or end of the intake or discharge section to the balance point, or point at which the axial velocity becomes zero, as indicated in dotted lines in Figs. 5 and 6. The maximum 20 axial air velocity is given, in each instance, as v_0 .

For the intake:

$$25 \quad v = v_0 \cdot \frac{\sinh \left(\frac{S(L_i - x)}{a\sqrt{C_i}} \right)}{\sinh \left(\frac{SL_i}{a\sqrt{C_i}} \right)} \quad (4)$$

$$30 \quad V = \frac{v_0}{\sqrt{C_i}} \cdot \frac{\cosh \left(\frac{S(L_i - x)}{a\sqrt{C_i}} \right)}{\sinh \left(\frac{SL_i}{a\sqrt{C_i}} \right)} \quad (5)$$

$$35 \quad p = P - \gamma \cdot \frac{v_0^2}{2g} \cdot \frac{\cosh^2 \left(\frac{S(L_i - x)}{a\sqrt{C_i}} \right)}{\sinh^2 \left(\frac{SL_i}{a\sqrt{C_i}} \right)} \quad (6)$$

40 For the discharge:

$$45 \quad v = v_0 \cdot \frac{\sin \left(\frac{S(L_d - y)}{a\sqrt{C_d}} \right)}{\sin \left(\frac{SL_d}{a\sqrt{C_d}} \right)} \quad (7)$$

$$50 \quad V = \frac{v_0}{\sqrt{C_d}} \cdot \frac{\cos \left(\frac{S(L_d - y)}{a\sqrt{C_d}} \right)}{\sin \left(\frac{SL_d}{a\sqrt{C_d}} \right)} \quad (8)$$

$$55 \quad p = \gamma \cdot \frac{v_0^2}{2g} \cdot \frac{\cos^2 \left(\frac{S(L_d - y)}{a\sqrt{C_d}} \right)}{\sin^2 \left(\frac{SL_d}{a\sqrt{C_d}} \right)} \quad (9)$$

It has been ascertained by investigation, and verified by tests, that when air is admitted from the end of the air-gap of a 60 machine having a long series of radial vents, the radial velocities approach a sinusoidal distribution, starting at a very low value in the radial vent nearest the end, and reaching a maximum at the balance point, as in-

dicated in curve A in Fig. 5. The utilization of end gap ventilation is, therefore, not conducive, in general, to the production of optimum conditions with approximately uniform radial velocities.

70 An important feature of our invention is to rely principally, for the ventilation, upon the air fed from the stator, the air-gap being closed at both ends in the ideal case. By the employment of a relatively large number 75 of annular intake and discharge chambers on the stator, as well as end ventilation on the air gap, the relative effect of the latter can be minimized to any degree desired. The occurrence of low radial velocities commonly resulting from end ventilation on the air gap can be avoided, in some measure, by proper design in accordance with principles explained later.

80 We will now explain the ideal arrangement of the stator ventilating system, assuming, for the moment, that the air-gap is closed at both ends. In such a system, a balanced arrangement would be employed 85 wherein the balance points would all be in the centers of the intermediate sections and at the ends of the end sections. We will consider the distribution of radial air velocity only, since the cooling effect depends upon the radial air velocity rather than the axial 90 air velocity. To design the system so that the difference between the maximum and the minimum radial velocities in any section may be within a given percentage, say 95 thirty percent, of the mean radial velocity, we turn to equations (5) and (8) for the 100 radial velocities in the intake and discharge ducts, respectively.

105 For the intake, V is a maximum for $x=0$, and a minimum for $x=L_i$, which, substituted in equation (5), gives

$$110 \quad V_{\min.} = \frac{v_0}{\sqrt{C_i}} \cdot \frac{1}{\sinh \frac{SL_i}{a\sqrt{C_i}}}$$

$$115 \quad V_{\max.} = \frac{v_0}{\sqrt{C_i}} \cdot \coth \frac{SL_i}{a\sqrt{C_i}}$$

$$120 \quad V_{\text{mean}} = \frac{v_0}{\sqrt{C_i}} \cdot \frac{1}{L_i} \int_0^{L_i} \frac{\cosh \frac{S(L_i - x)}{a\sqrt{C_i}}}{\sinh \frac{SL_i}{a\sqrt{C_i}}} \cdot dx$$

$$= \frac{v_0 a}{SL_i} \quad 120$$

If we put

$$125 \quad \frac{SL_i}{a\sqrt{C_i}} = \alpha, \quad 125$$

we shall have for the intake,

$$130 \quad \frac{V_{\max.} - V_{\min.}}{V_{\text{mean}}} = \alpha \cdot \frac{\cosh \alpha - 1}{\sinh \alpha} \quad (10)$$

For the discharge, V is a maximum for

$y=L_d$, and a minimum for $y=0$, which, substituted in equation (8), gives

$$5 \quad V_{\min.} = \frac{v_0}{\sqrt{C_d}} \cdot \cot \frac{SL_d}{a\sqrt{C_d}}$$

$$10 \quad V_{\max.} = \frac{v_0}{\sqrt{C_d}} \cdot \frac{1}{\sin \frac{SL_d}{a\sqrt{C_d}}}$$

$$15 \quad V_{\text{mean}} = \frac{v_0}{\sqrt{C_d}} \cdot \frac{1}{L_d} \int_0^{L_d} \frac{\cos \frac{SL_d - y}{a\sqrt{C_d}}}{\sin \frac{SL_d}{a\sqrt{C_d}}} dy \\ = \frac{v_0 \cdot a}{SL_d}.$$

20 If we put

$$\frac{SL_d}{a\sqrt{C_d}} = \beta,$$

25 we shall have, for the discharge,

$$25 \quad \frac{V_{\max.} - V_{\min.}}{V_{\text{mean}}} = \beta \cdot \frac{1 - \cos \beta}{\sin \beta}. \quad (1)$$

$$0.79 = \frac{0.2 \cdot L_i}{2.1 \sqrt{1.30}}, \text{ or } L_i = 9.45 \text{ vents, say 9.5 vents,}$$

and

$$0.75 = \frac{0.2 \cdot L_d}{2.1 \sqrt{1.07}}, \text{ or } L_d = 8.14 \text{ vents, say 8.5 vents.}$$

55 Assigning values to C_i and C_d , we find, for the particular machine in question, that the number of intake radial vents per half-section, multiplied by the ratio of the minimum area of one radial vent to the area of 60 the air-gap, should be about 0.9, and the corresponding number of discharge radial vents, multiplied by said ratio, should be 0.8. In general, from Fig. 3, it will be seen

65 that any value of $L \cdot \frac{S}{a}$ less than unity will

give fairly good results, where a very high degree of uniformity is not required. With an arrangement employing one center discharge, the radial vents would be grouped 70 in the order

$$8.5 + 19 + 17 + 19 + 8.5 = 72 \text{ vents,}$$

as indicated schematically in Fig. 4.

75 We will now consider a system of ventilation in which the air is fed both from the end-bell and from the stator. The formulæ (4) to (9) provide means for determining the axial and the radial air velocity at any point, and they thus provide means for so determining the length of the end discharge portion of the core in relation to the other discharges and intakes, that the ultimate variation in radial air velocity shall not exceed a certain proportion of the mean radial

We have plotted the two functions,

$$30 \quad \alpha \cdot \frac{\coth \alpha - 1}{\sinh \alpha}$$

and

$$35 \quad \beta \cdot \frac{1 - \cos \beta}{\sin \beta},$$

against α and β in Fig. 3. The application is obvious. Suppose we wish to have a variation of less than thirty percent between the maximum and minimum radial velocities. Then, from the curve, we find $\alpha=0.79$ and $\beta=0.75$, whence, from the definition of α and β ,

$$40 \quad 0.79 = \frac{SL_i}{a\sqrt{C_i}}$$

and

$$45 \quad 0.75 = \frac{SL_d}{a\sqrt{C_d}}.$$

Generally, S , a , C_i and C_d are determined 50 and fixed quantities. In the case of the machines for which the curves in Figs. 5 and 6 were plotted, $S=0.2$ sq. ft., $a=2.1$ sq. ft., $C_i=1.30$, $C_d=1.07$. Then,

air velocity. No general proof can be given of this statement, as the work requires the solution of a system of simultaneous transcendental equations, which have to be solved by cut and trial.

90 As an illustration of the principles just explained, we have shown, in curve A of Fig. 5, the radial velocities of the ventilation as originally laid out, and we have superimposed, in curve B, an improved arrangement in accordance with our invention. It will be noted that the original arrangement gave very poor ventilation near the ends, with radial velocities running down to 400 feet per min. per one-inch of water pressure. By the redesign in accordance with the principles herein enunciated, utilizing a smaller number of ducts in the discharge groups at the ends, the initial radial velocity was brought up to 2300.

100 A further illustration of a design in accordance with our invention is shown in Fig. 6, illustrating a very desirable arrangement in another stator frame.

The foregoing discussion is based upon 110 the assumption that the rotor is stationary. Tests indicate that the radial velocities are, if anything, more uniform when the rotor is rotating.

115 While our invention has been described and explained with reference to a certain

mathematical treatment, we do not wish to be limited altogether thereto. It is known that certain errors and approximations are involved, as hereinabove pointed out, and 5 also probably larger errors are introduced by the integration of infinitesimal increments, whereas there are only a finite number of vents. However, the results obtained are sufficiently accurate to secure a very fair 10 insight into the general principles involved. We desire, therefore, that our claims shall be given the broadest interpretation consistent with the improvement over the prior art.

15 We claim as our invention:

1. A dynamo-electric machine having a rotor and a stator with an air-gap therebetween, said stator embodying a ventilating system comprising a plurality of groups of 20 radially extending ventilating spaces surrounding the air-gap, intake chambers surrounding one or more groups of radial spaces for conducting a cooling fluid radially inwardly, and discharge means surrounding the remaining groups of radial spaces, the cross-sectional areas of the air-gap and radial spaces, the numbers of radial spaces in the respective groups, and the configurations of the ventilating paths being 25 such that all groups have substantially the same minimum radial velocities and the same maximum radial velocities of the cooling fluid.

2. A dynamo-electric machine having a 30 rotor and a stator with an air-gap therebetween, said stator embodying a ventilating system comprising a plurality of groups of radially extending ventilating spaces surrounding the air-gap, intake chambers surrounding one or more groups of radial spaces for conducting a cooling fluid radially inwardly, discharge means surrounding the remaining groups of radial spaces, entrance chambers for cooling fluid at the two ends 40 of the air gap, and means for maintaining approximately the same pressures in said intake and entrance chambers, the number of radial spaces in the end groups being so chosen with respect to the numbers of radial 45 spaces in the intermediate groups and the ratio of the radial space areas to the air gap area, that approximately equal average radial velocities are obtained in all of the groups.

55 3. A dynamo-electric machine having a rotor and a stator with an air-gap therebetween, said stator embodying a ventilating system comprising a plurality of groups of radially extending ventilating spaces surrounding the air-gap, intake chambers surrounding one or more groups of radial spaces for conducting a cooling fluid radially inwardly, a discharge means surrounding the remaining groups of radial spaces, entrance chambers for cooling fluid

at the two ends of the air gap, and means for maintaining approximately the same pressures in said intake and entrance chambers, the number of radial spaces in the end groups being so chosen with respect to the 70 numbers of radial spaces in the intermediate groups and the ratio of the radial space areas to the air gap areas, that approximately equal minimum radial velocities are obtained in all of the groups. 75

4. The combination with a dynamo-electric machine having a rotor and a stator having an air-gap therebetween, said stator having a plurality of radially extending ventilating passages surrounding said air-gap, of means for supplying a cooling fluid to the peripheries of a plurality of radial passages and for discharging said cooling fluid from a plurality of other radial passages, the intake radial passages being 80 grouped in one or more sections and the discharge radial passages being grouped in a plurality of sections alternating with said intake groups, and the numbers of radial 85 passages per group and the cross-sectional areas of the radial passages being so chosen that the difference between the maximum and minimum radial velocities in any group shall not exceed approximately thirty per cent of the average radial velocity in said 90 group. 95

5. The combination with a dynamo-electric machine having a rotor and a stator having an air-gap therebetween, said stator having a plurality of radially extending 100 ventilating passages surrounding said air-gap, of means for supplying a cooling fluid to the peripheries of a plurality of radial passages and for discharging said cooling fluid from a plurality of other radial 105 passages, the intake radial passages being grouped in one or more sections and the discharge radial passages being grouped in a plurality of sections alternating with said intake groups, the number of radial passages 110 L_i per half-group of intake radial passages being approximately

$$L_i = \alpha \cdot \frac{a}{S} \cdot \sqrt{C_i},$$

115

α being an angle in radians such that

$$\alpha \cdot \frac{\cosh \alpha - 1}{\sinh \alpha} = r,$$

120

r being a predetermined desired ratio between the velocity variation in any group and the mean velocity therein, α being the cross-sectional area of the airgap, S being the minimum cross-sectional area of a radial passage, and C_i being a constant determined by experiment for the particular machine, usually having a value between the limits 1.05 and 1.3 for different machines, and the number of radial passages L_a per half-group 125 130

of discharge radial passages being approximately

$$L_d = \beta \cdot \frac{a}{S} \cdot \sqrt{C_d}, \quad 5$$

β being an angle in radians approximately such that

$$\beta \cdot \frac{1 - \cos \beta}{\sin \beta} = r, \quad 10$$

and C_d being a constant determined by experiment for the particular machine, usually having a value between the limits 0.6 and 1.2 for different machines.

15 6. The combination with a dynamo-electric machine having a rotor and a stator having an air-gap therebetween, said stator having a plurality of radially extending ventilating passages surrounding said air-gap, of means for supplying a cooling fluid to the peripheries of a plurality of radial passages and for discharging said cooling fluid from a plurality of other radial passages, the intake radial passages being grouped in one or more sections and the discharge radial passages being grouped in a plurality of sections alternating with said intake groups, and the number of radial passages per half-group, multiplied by the minimum cross-sectional area of a single radial passage and divided by the cross-sectional area of the air gap, being less than unity.

25 7. The combination with a dynamo-electric machine having a rotor and a stator having an air-gap therebetween, said stator having a plurality of radially extending ventilating passages surrounding said air-gap, of means for supplying a cooling fluid to the peripheries of a plurality of radial passages and for discharging said cooling fluid from a plurality of other radial passages, the intake radial passages being grouped in one or more sections and the discharge radial passages being grouped in a plurality of sections alternating with said intake groups, and the number of radial passages per half-group of intake radial pas-

sages, multiplied by the minimum cross-sectional area of a single radial passage and divided by the cross-sectional area of the air gap, being approximately 0.9.

8. The combination with a dynamo-electric machine having a rotor and a stator having an air-gap therebetween, said stator having a plurality of radially extending ventilating passages surrounding said air-gap, of means for supplying a cooling fluid to the peripheries of a plurality of radial passages and for discharging said cooling fluid from a plurality of other radial passages, the intake radial passages being grouped in one or more sections and the discharge radial passages being grouped in a plurality of sections alternating with said intake groups, and the number of radial passages per half-group of discharge radial passages, multiplied by the minimum cross-sectional area of a single radial passage and divided by the cross-sectional area of the air gap, being approximately 0.8.

9. The combination with a dynamo-electric machine having a rotor and a stator having an air-gap therebetween, said stator having a plurality of radially extending ventilating passages surrounding said air-gap, of means for supplying a cooling fluid to the peripheries of a plurality of radial passages and to the ends of the air-gap and for discharging said cooling fluid from the remaining radial passages, the intake radial passages being grouped in one or more sections and the discharge radial passages being grouped in a plurality of sections alternating with said intake groups, the areas of the radial passages and the numbers of radial passages in the respective sections being so chosen with respect to the air-gap area that the ultimate variation in radial air velocity shall not exceed about thirty per cent of the mean radial velocity.

In testimony whereof, we have hereunto subscribed our names this 14th day of June, 1923.

DONALD BRATT.
CARL J. FECHHEIMER.
